UNITED STATES PATENT OFFICE

HENRY A. DAUDE, OF KILLEEN, TEXAS

PORTABLE GARDEN HOE VISE

Application filed April 8, 1932. Serial No. 604,093.

This invention relates to an unusual and apparently novel device for clamping and holding a gardening hoe in a convenient and steady position while sharpening the cutting edge of the hoe blade with a suitable file.

Otherwise stated, the invention is in the nature of a hoe filing clamp such as may be conveniently herein referred to as a portable vise, the same being constructed for placement on the ground or other support to hold the blade of the hoe in a steady inverted position while filing the blade thereof.

The particular structural details selected for manufacture and construction of the improved appliance will become more readily apparent from the following description and drawings. In the accompanying illustrative drawings:

Figure 1 is a top plan view of a device as constructed strictly in accordance with the preferred embodiment of the invention.

Figure 2 is an end view thereof showing the hoe in inverted position.

Figure 3 is a longitudinal sectional view taken approximately through the center of the device.

Figure 4 is a section on the line 4—4 of Figure 3.

Figure 5 is a section on the line 5—5 of Figure 4.

Figure 6 is a perspective view of the clamping lever.

Figure 7 is a detail section on the line 7—7 of Figure 2.

The base is in the nature of a suitably shaped and balanced frame and is generally designated by the numeral 8. It preferably comprises a substantially V-shaped member 9 formed from flat strap metal and having its diverging portions terminating in extremities bent upwardly as indicated at 10 to provide uprights to accommodate the means forming the rack or vise proper.

As seen in Figure 2 this means comprises an upper cross strip 11 riveted to the uprights and having its upper edge portion projecting above the uprights. Fastened to this cross strip are relatively short cleats 12 and located between the parts 11 and 12 are spacing plates 13 whose upper edges terminate in

a plane below the corresponding edges of the parts 11 and 12 to form a longitudinally elongated groove 14 providing a seat for reception of the blade 15 of the hoe when said blade is placed in an inverted position as seen in Figures 2 and 3.

It will be observed that the intermediate portion of the header strip 11 is provided with a bent portion 15 to accommodate the shank 16 and attached end 17. Incidentally the hoe handle is denoted in Figure 3 by the numeral 18.

The numeral 19 in Figure 2 designates a supporting member fastened to the upright 10 and formed intermediate its ends with a hoe 20 to accommodate the reduced end 21 of a clamping lever 22. The connection at this point between the lever and supporting member 19 is made through the medium of a cotter key 23 as seen in Figure 2. The lever is provided as a clamping member and has a hook 24 to engage over the shank of the hoe 16 as seen in Figure 3 when the hoe is placed in the vise for filing.

The free end portion of the lever extends through a guard 25 of the type represented in Figure 4. This guard is made up of a pair of metal strap members 26 and 27 joined together in spaced relation as seen in Figure 4, the upper end of the member 27 being provided with a U-shaped seat 28 to receive the hoe handle. Moreover, the member 27 carries a toothed rack bar 29 with which a retaining detent or pawl 30 on the lever is selectively engageable.

As before stated, the device is relatively small and of such weight and form as to make it readily portable so that it can be carried from place to place in the field while the hoe is being used. Whenever the hoe blade becomes needlessly dull, the hoe is placed in the clamp or vise as shown in Figure 3. In other words, the hoe is inverted, the blade is engaged in the seat or groove 14 and the handle 18 is placed in the hanger 28. Then the hook 24 on the retaining lever 22 is engaged over the shank of the hoe and the free end portion of the lever is pulled down to the required position so as to permit the pawl and rack mechanism to come into play for holding the

lever in this set position. Consequently the hoe is clamped firmly in the vise in such a manner as to permit the hoe to be held steady while resharpening the dulled edge of the blade.

6 I claim:

1. A portable garden hoe holding vise of the class described comprising a frame having a right angularly positioned rack at one end thereof, handle seating means on the frame disposed parallel to said rack and spaced longitudinally therefrom, a lever pivotally and detachably connected at one end to the rack and provided intermediate its ends with a hook to engage over the shank of the hoe, a relatively stationary rack bar mounted on the frame, and a detent carried by the lever and engageable with the teeth of the rack bar.
- 10 2. A garden hoe holding device of the class described comprising a portable support including a frame having laterally directed end portions, spaced parallel members attached to said end portions, an intervening plate between said members defining a groove for reception of the edge of the hoe blade, a cross piece attached to the aforesaid end portion, a lever pivotally connected thereto, a guard on said frame, the free end portion of the lever 15 extending through and beyond the guard, a toothed rack bar mounted within the confines of the guard, said lever being provided with a detent engageable with the teeth of said rack bar, one of the members of said guard being formed with a U-shaped seat for reception of the adjacent portion of the hoe handle, and said lever being provided with a hook engageable with the shank of the hoe.
